ALICE BALLARD HANCHETT, OF DETROIT, MICHIGAN

COIN CHANGING MACHINE

Application filed July 13, 1931. Serial No. 550,492.

This invention relates to improvements in change making machines and more particularly to a mechanism for the purpose which is of simple, compact design arranged to receive coins of different denominations and to deliver a plurality of coins or tokens of a smaller denomination, aggregating in value, the value of the coin inserted.

A further object is to provide a change maker in the form of a self contained unit adapted to be operated entirely independent of any vending or other machine requiring coins of a certain size or denomination to operate the same in delivering merchandise or service, such as those machines which are commonly provided for the general use of the public.

It is also an object to provide a mechanical unit for the purpose, which may be used as an accessory to be built into, or attached to existing types of coin operated vending or service dispensing machines, as a convenient source of the required size of coin or token for the operation of such machines.

For the purpose of brevity in the description, I will refer hereinafter to the various sized coins, as quarters, dimes, and nickels as being the coins which the present embodiment is designed to handle, but it is to be understood that the use of these terms shall not be considered as limiting the device to the employment of coins of these particular denominations, since, to adapt the device to use domestic coins of other sizes or to foreign coins, would only involve changes in dimensions of certain mechanical parts and would not affect the general construction.

The present embodiment of this invention is disclosed in detail in the accompanying drawings in which—

Figure 1 is a front elevation of a device illustrative of an embodiment of the present invention, with a key coin receiving mechanism shown in its neutral position;

Fig. 2 is a sectional detail on line C—C of Figure 1;

Fig. 3 is a detail view showing the position of the coin receiving parts in their operat-

ed position after having received a dime and with the front cover of the casing removed;

Fig. 3A is a sectional detail on the line E—E, of Figure 3, to show a coin engaging lug;

Fig. 4 is a sectional detail similar to that of Figure 2 and taken upon the line B—B of Figure 1 through the quarter receiving slot;

Fig. 5 is a detail view similar to that of Figure 3 showing the parts in position after having received a quarter;

Fig. 6 is a vertical section through all except a lower end portion of the casing, upon the line A—A of Figure 1;

Fig. 7 is a sectional detail upon the line G—G of Figure 6 showing the position assumed by coin discharge parts when engaging five nickels and when the key coin receiving mechanism is in the position shown in Figure 5;

Fig. 8 is a detail view similar to that of Figure 7, with the coin discharge parts in the position assumed when the key coin is a dime and when the receiving mechanism is in the position shown in Figure 3;

Fig. 9 is a detail, the same as that of Figures 7 and 8, with these parts in the neutral position as shown in Figure 1;

Fig. 10 is a transverse vertical section on the lines F—F of Figures 6 and 11, showing coin discharge mechanism and actuating means as arranged in the casing; and

Fig. 11 is a horizontal section upon the line D—D of Figures 10 and 6.

In general, the device consists of two coacting groups of elements; the coin receiving group and the coin discharge group, the two groups being arranged to cooperate when a proper coin is inserted to serve as a key or driver to operate the discharge mechanism when the coin receiving mechanism is operated.

For the sake of clarity I will describe the groups, one at a time, first taking up the coin receiving mechanism. A coin of the proper denomination is inserted in one of the corresponding openings 1 or 2 in a front cover plate 6' of a suitable casing 6 until it rests against a plate 3 secured between said

55

65

75

90

95

100

plate 6' and the casing front wall. Grooves or slots 4 and 5 are cut in the back of said front cover plate 6' leading from said openings 1 and 2, respectively, to provide guideways to convey the coins by gravity to the positions *x* or *y*, where it is in a position to serve as a key between a driver or abutment 7 integral with the back of a driver plate 12 and an engaging lug 8 or 9 on plate 10, 10 it being caught and stopped between these parts.

The openings 1 and 2 and grooves 4 and 5 are accurately machined to allow the least practical clearance around a newly minted 15 coin in order to protect the entire device from the insertion of improper, damaged or counterfeit coins or slugs and to avoid cheating, or the jamming of the mechanism.

With a coin in a key position *x* or *y*, when 20 the handle 11 is turned in the direction of the inserted coin, the various parts assume positions shown in Figures 3 or 5 as the case may be. The driver 7 forms an integral abutment on plate 12 which is retained and 25 keyed to the handle 11 by means of nut 13 and dowel 14, and the shaft 15 is an extension of the handle 11. To prevent moving the handle the wrong way or away from the inserted coin, a stud 16 is set into the back of 30 plate 6' so as to be engaged by the coin as it is carried around by the turning of the handle and stop such movement by the jamming of the coin between this stud 16 and one of the lugs 8 or 9. The rocker plate 10 35 is pivoted to an arm 17 mounted to turn upon the shaft 15, by means of a loose rivet 18 so that when the coin drives the plate 10 to one side or the other, the arm 17 is rotated upon said shaft 15 to approximately 40 one or the other of the positions indicated in Figures 3 and 5, and this movement serves to actuate the coin discharge device, as hereinafter set forth.

When the coin reaches the positions *a* or *b* 45 (Figures 3 or 5) the lug 8 or 9 which has been held in engagement with the coin by contact against a circular guide surface 21 on plate 3, now falls away from the coin as it reaches the end of the circular pathway, 50 thus permitting the driver 7 to advance a little farther and so eject the coin into the tray 22a. Figures 3 and 5 show coins at the point of falling away.

As soon as the coin falls, the handle and 55 all of the parts connected thereto and actuated thereby, are returned to neutral position shown in Figure 1, ready to be again operated. This return movement is effected by means of spring loaded parts attached to the rear end portion of shaft 15, and consist of a cam 22 secured to the shaft 15 by a screwed stud 23 which is extended to form a lever to the upper free end of which is attached one end of a pull spring 24, the opposite or upper end of which is anchored to a rigid arm 60

25 on the casing 6. These parts are shown partly in section in Figure 6 and in elevation in Figures 7 and 8 with said parts in their extreme positions of movement, said spring 24 acting on the lever 23 exerting a 70 force to return the shaft and connected parts to approximately neutral or intermediate position after manual operation.

In order to further insure an accurate neutral position, a spring loaded plunger 26 75 having a lateral stud 27 is provided, so that said stud is caused to ride upon the surface of said cam 22 which is formed with a deep depression or notch 27a intermediate its ends, into which said stud drops to insure 80 centralization of the parts and to hold these parts yieldingly in neutral position as shown in Figure 9.

The mechanism for discharging a certain 85 number of coins in exchange for either the coin 1 or 2 inserted and of an aggregate value equal to the value of the inserted coin, comprises a reciprocating slide 28 having holes 29 and 30 arranged to receive coins from a magazine or tube 31 down which 90 they are fed by gravity, said slide being arranged to receive a number of coins through said holes therein and move these coins sideways until they are permitted to fall out of said slide 28 by gravity into a surrounding 95 hopper 32 which is arranged to convey them to a delivery pocket 33 where the operator may take them out with his fingers.

Reciprocating movement of said slide 28 is effected by an oscillating motion of said 100 arm 17 (as previously described) which motion is transmitted through a gear 34 to a rack 35 secured to the bottom of said slide 28. A cam 36 is secured by screws 37 and dowels 38 to turn with said gear 34 and arm 105 17, this assembly being freely rotatable on the shaft 15, and this cam 36 is formed with surfaces 39 and 39a, one surface, 39a being at a greater radial distance from the axis of the cam, than the surface 39, this cam being 110 arranged with its external cam surface directly below the lower end of the magazine tube 31 and of a width equal to or greater than the diameter of said tube, so that coins dropping into the holes 29 or 30 in said 115 slide 28 will rest upon said cam surface and be supported thereby until slid laterally therefrom by the endwise movement of said slide. The number of coins which will drop down from said magazine tube is determined 120 by the position of said cam 36, as a greater number will be discharged when the surface 39 is opposite the magazine, than when the surface 39a is uppermost, and as the position of said cam is determined by which denomination of coin is inserted in the respective openings 1 or 2, the proper surface 39 or 39a will be in position to permit the right 125 number of coins to discharge from the magazine in exchange for the inserted coin. Fig- 130

ure 7 shows the cam 36 in position to permit the escape of five coins, and in Figure 8 said cam is shown in position to permit the discharge of two coins only. In Figure 9, 5 said slide 28 is shown in mid or neutral position with both of the said holes 29, 30 out of alignment with the stack of coins in the magazine and supporting the entire stack, all of the parts of the machine being in 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 leasing a plurality of coins from said magazine and including means for determining the number of coins to be released thereby, said plurality of coins corresponding in aggregate value to the value of the coin received from one of said guideways.

5. In a machine of the character described, the combination of means having guideways and into which guideways coins 10 may be inserted, a coin magazine, a pivotally supported driver member adapted to be oscillated beneath adjacent guideways, means on said driver member for receiving coins from the lower ends of said guideways and 15 releasably holding the same, a handle for operating said driver member, means beneath said magazine for receiving a plurality of coins therefrom and discharging the same, and including means for limiting the number of coins to be released thereby to a number 20 corresponding in aggregate value to the value of the coin received from said guideway and means for transmitting motion from said driver member to said means beneath said magazine, for actuating the same.

6. In a machine of the character described, the combination of means having guideways and into which guideways coins 30 may be inserted, a coin magazine, a pivotally supported driver member adapted to be oscillated from one to the other of adjacent guideways, a rocker member pivotally attached to said driver and formed adjacent each end to engage a coin dropping from the lower end of one of said guideways and releasably clamp said coin between it and said driver to be carried downwardly by the oscillation of said driver, means for holding 35 said rocker member against rocking movement upon said driver and for releasing the same to permit rocking movement to release said coin, means beneath said magazine to release a plurality of coins therefrom and 40 including means for limiting the number of coins to be released thereby, and means for transmitting motion from said driver to operate said releasing means beneath said magazine.

60 7. In a machine of the character described, the combination of coin receiving means into which coins of different denominations may be inserted, operating means for operating said coin receiving means in a direction determined by the inserted coin, a coin magazine, and means actuated by said operating means for discharging a plurality of coins from said magazine and including means for limiting the number of coins so discharged, to equal in aggregate value, the value of the inserted coin.

65 8. In a machine of the character described, the combination of means having guideways adapted to receive coins in different denominations, coin receiving means to receive

coins from said guideways and adapted to be moved from coin receiving position opposite one guideway to coin receiving position opposite an adjacent guideway, a coin magazine, and means for discharging a plurality of coins from said magazine corresponding in aggregate value to the value of said coin received from said guideway and operatively connected with said coin receiving means to move simultaneously therewith.

70 9. In a machine of the character described, the combination of means having guideways adapted to receive coins of different denominations, coin receiving means to receive coins from said guideways and adapted to be moved from coin receiving position opposite one guideway to coin receiving position opposite an adjacent guideway, a coin magazine, means for discharging coins from said magazine and including a member movably supported beneath said magazine to support coins therein and movable with said coin receiving means to different positions and selectively discharge a plurality of coins 80 of an aggregate value equal to the value of the coin received by said receiving means.

75 10. In a machine of the character described, the combination of means having guideways adapted to receive coins of different denominations, coin receiving means pivotally supported intermediate the lower ends of adjacent guideways to be swung laterally across said ends to and from a position to receive coins from both of said guideways and laterally and downwardly from said position to discharge the coin received thereby, means for preventing rotation of said coin receiving means in a direction opposite to that in which it is swung to discharge the received coin, a coin magazine, and selective means beneath the lower end of said magazine for discharging a plurality of coins therefrom of aggregate value equal to the value of the inserted coin, said selective means being operated by swinging movement of said receiving means in both directions.

80 11. In a machine for the purpose described, the combination of means having parallel guideways for coins of different diameters, a driver plate pivotally supported for swinging movement beneath the lower ends of said guideways, an abutment on said driver plate, a rocker member pivotally attached to said driver plate and formed at its ends to engage coins received from said guideways and clamp the same between said formed ends and said abutment, a member having a semi-circular path concentric with the pivotal support of said driver plate to engage a coin held between said abutment and said formed ends of said rocker member, a handle for turning said driver plate, a coin magazine, and means beneath said 115 120 125 130

magazine operatively connected to said driver plate for selectively discharging a plurality of coins therefrom.

12. In a machine of the character described, the combination of pivotally supported means for receiving, holding and discharging coins of different diameters, means for actuating said pivotally supported means, a coin magazine, a member rotatable with said actuating means and supported beneath the discharge end of said magazine to support coins therein and having coin supporting surfaces at different radial distances from the axis of said member, and means to effect the discharge from said magazine of coins differing in numbers, depending upon which of said surfaces is in coin supporting position.

13. In a machine of the character described, the combination of a member having parallel guideways to receive coins of different diameters, a driver member pivotally supported adjacent the lower ends of adjacent guideways to swing across said lower ends thereof, a member pivotally supported adjacent said driver member to turn independently thereof and means on said driver member and said member adjacent thereto to receive a coin therebetween from one of said guideways, said coin serving, when so received, as a key to connect said members to turn together, and means for releasing said coin from between said members at the ends of the swinging movement of said driver member.

14. In a machine of the character described, the combination of a member having parallel guideways to receive coins of different diameters, a driver member pivotally supported adjacent the lower ends of adjacent guideways to swing across said lower ends thereof, a member pivotally supported to turn upon an axis coincident with the axis of turning movement of said driver member and to swing adjacent thereto, a member pivotally attached to one of said members and having portions to engage the edge of a coin received from one of said guideways and clamp the same between said portion and the other of said members, and means for holding said pivotally attached member in coin clamping position and to release the same at each end of the swinging movement of said driver.

15. In a machine of the character described, the combination of a member having parallel guideways to receive coins of different diameters, an operating handle, a shaft to the outer end of which said handle is secured, a driver member connected to turn with said handle adjacent the lower ends of said guideways and transversely thereof, an arm mounted upon said shaft free to turn thereon independently of said driver member, a member on said arm

clamped between it and said driver member, a coin received from one of said guideways to form a key for connecting said arm and driver to turn together, and a member having a semi-circular guide to hold said received coin in its clamped position and release the same at the ends of said guide.

16. In a machine of the character described, the combination of a member having parallel guideways to receive coins of different diameters, an operating handle, a shaft upon the outer end of which said handle is secured, a driver plate to turn with said handle transversely of and adjacent the lower ends of said guideways, a receiver free to turn upon said shaft adjacent said driver plate and adapted to receive a coin from either of said guideways when said handle is in mid-position, means on said driver plate to engage a coin received by said receiver and cause said driver plate and receiver to turn together in the same direction, and means for guiding and holding said received coin in position to connect said driver and receiver during turning of said handle and driver plate in either direction from mid-position and to release said coin after it has been carried from beneath its guideway by the turning of said handle and driver plate.

In testimony whereof I affix my signature.

ALICE BALLARD HANCHETT.
